UNITED STATES PATENT OFFICE.

MOTT G. GILLETTE, OF GARDEN CITY, NEW YORK

BUTTONLESS TROUSERS.

Application filed May 12, 1923. Serial No. 638,595.

The invention relates to improvements in a trouser construction.

It has been recognized by those skilled in the art that with trousers as now generally constructed the belt encircling the hip portion thereof often presents an unsightly appearance, and a still further objection to the use of the general type of trousers is that the buttons receiving the suspenders are exteriorly disposed, being rather unsightly, and furthermore offering projections which frequently engage stationary objects, causing the button to be severed and the trouser to be torn.

15 It is an object of this invention to provide both suspender and belt supporting means for trousers where the belt is located for the greater portion of its length inside the waist line of the trouser, and in which construction 20 the suspender is attached to an eye opening interiorly of the trouser and secured to a stiffening and retaining element.

More specifically the invention relates to the suspender attaching means for the trouser, which comprises a strip of heavy material interposed between the trouser cloth at the waist line and a lining, and carrying a plurality of spaced metallic eyes opening 25 interiorly of the trouser and adapted to receive complementary hooks arranged on the suspender tabs.

In the accompanying drawings, I have shown a preferred embodiment of the invention, in which:

35 Fig. 1 is a perspective view;

Fig. 2 is a similar view with the front flap open; and

Fig. 3 is a sectional view.

Referring now more particularly to the 40 drawings, wherein like reference characters indicate corresponding parts, the numeral 1 designates a pair of trousers, which may be of any conventional type, having the usual hip engaging portion 2.

45 The hip engaging portion of the trousers is provided with a plurality of interior loops 3 extending therearound, and is also formed with slits 4 and 5 extending therethrough near the front or flap portion of the trouser.

50 Underlying each slit is a shield 6, which serves to cover the slit portion and prevent exposure of materials beneath the waist band at times when the belt to be now described is not in use.

55 The flaps 3 receive a belt 7, which may be of the usual type, extending around the hip

engaging portion of the trousers, the ends of the belt passing through the slits 4 and 5 and being united by the buckle 8. This permits the trousers to be used with a belt, and 60 the belt is obviously hidden from view, except the ornamental portion thereof that is the buckle 8, which is exposed. In lieu of flaps 3, a continuous strip could be extended around the inner side of the hip engaging 65 portion of the trousers to form a housing for the belt.

It is desirable at times to use with the belt suspender supporting means, and certain users also prefer to either employ a belt or 70 suspenders separately. The invention comprehends suspender attaching means for the trousers, comprising an inner band of stiff relatively non-flexible material 9 that may be of a heavy fabric which is interposed between the upper portion of the hip engaging 75 part of the trousers, and a trouser lining 10 of some relatively soft material. The band 9 may be constructed of heavy canvas and lies between the fabric of the trousers and the lining 10, both the fabric of the trousers and the lining being re-bent as shown at 11 at the upper end thereof to assist in providing a seat for said band 9. The band 9 is held in position preferably by stitching 12, 80 and extends entirely around the waist line 85 of the trousers. This band may be perforated near its edges to receive the stitching.

At separated points the band 9 and the 90 interlining 10 receives the metallic eyes or sockets 13, which sockets are tightly riveted or clamped in position, and are, as clearly shown, principally supported by the relatively non-flexible band 9. Six of the sockets 95 are preferably used, constituting means by which the suspender tabs are attached to the trousers. In Fig. 3 I have shown a section of one suspender tab, but this is illustrative of all others. This tab 14 carries a 100 metallic hook 15, which is adapted to spring into the eye or socket 13 on the principle of the well known glove fastener, and will be firmly held in its attached position.

105 It will be apparent that the socket 13 terminates at its inner side substantially flush with the lining, so as to form no projecting part to irritate the user, and that by furthermore mounting this socket in the non-flexible band 9 the upper edge of the trouser will not 110 buckle or bend when suspenders are attached thereto. The trouser along its upper edge

will have a straight and pleasing surface, and obviously the strain will be largely taken by the band and serve to eliminate danger of the attaching means for the suspender tearing or injuring the cloth of the trouser.

Having thus described the invention, what I claim is:

A trouser structure having a hip engaging portion composed of fabric, a thin interior lining secured to the hip engaging portion of the trousers near the upper end thereof, circular rows of stitching forming between said lining and said fabric a continuous open circular pocket, a substantially non-bendable circular band housed within said pocket, cir-

20
25
cular rows of stitching for holding said band in position in the pocket passing therethrough adjacent its upper and lower edges, a plurality of spaced metallic fasteners fixedly secured to said non-bendable band and passing through said thin lining with open ended sockets at the inner side of the lining, said fasteners being obscured from view at the exterior of the trousers by the fabric constituting the hip engaging portion thereof and being capable of supporting the trousers without causing a buckling of the fabric when attached to supporting clasps.

In testimony whereof I affix my signature.

MOTT G. GILLETTE.
